DISTILLATION PROCESS FOR HYDRO-CARBON OILS

John S. Wallis and Charles T. Chave, New York,
N. Y., assignors, by mesne assignments, to
American Locomotive Company, New York,
N. Y., a corporation of New York

Application February 23, 1934, Serial No. 712,536

5 Claims. (CL 196—77)

Our invention relates to a distillation process for hydrocarbon oils and more particularly to a vacuum distillation process in which a steam jet pump is used to transfer steam and/or uncondensed overhead products from a stripping or flash tower at high vacuum to a fractionating tower at medium vacuum.

It is known that vapor condensers may be used to create a condition of low absolute pressure in a flash evaporation zone or in a stripping zone. This pressure is, however, limited by the temperature of the available cooling water. An even lower absolute pressure can be obtained by using a thermo-compressor or steam jet such as is disclosed in the Kramer Patent 1,619,348 or in the Schulze Patents 1,488,709 and 1,934,150. It is to be noted, however, that in the process as disclosed in the Kramer patent, the steam from the thermo-compressor is discharged directly into a barometric condenser. The Schulze process is applicable, particularly, to dry vacuum distillation wherein no stripping steam is used in either a flash evaporation zone or in a stripping section. It is an object of our invention to reduce the total amount of steam required when relatively large amounts of vapors are being withdrawn by a thermo-compressor or steam jet pump from a flash evaporation or stripping tower by condensing hydrocarbon vapors out of the steam, reheating the condensate, and separately introducing the heated condensate and the uncondensed products to a fractionating tower maintained at a higher absolute pressure than that in the flash or stripping tower.

It is a further object of our invention to provide a process for obtaining a low absolute pressure in a flash tower or stripping tower by means of a steam jet pump or thermo-compressor while utilizing the steam from the pump or compressor to secure increased vaporization in a fractionating tower at a low temperature, as a result of the partial pressure effect.

It is a further object of our invention to provide a novel double flash high vacuum distillation system for producing low penetration asphalt and a high yield of cylinder stock from an asphaltic reduced crude petroleum oil.

Another object of our invention is to provide a double flash high vacuum distillation system in which the asphaltic flux bottoms from a fractionating tower maintained at high vacuum are externally heated, flashed at a higher wet or dry vacuum maintained by a thermo-compressor or steam jet pump, and light overhead products are

returned with the exhaust steam to the fractionating tower.

A still further object of our invention is to provide an external stripping or flash tower which is maintained under a high vacuum by means of a thermo-compressor and from which the overhead products are returned to a fractionating tower either with the steam from the thermo-compressor or separately as a condensate.

In the accompanying drawings which form part of the instant specification and which are to be read in conjunction therewith and in which like reference numerals refer to like parts throughout the several views;

Figure 1 is a schematic drawing of a preferred embodiment of our invention in which the vapors from a flash or stripping tower are condensed and reheated before introduction to a fractionating tower and in which a thermo-compressor discharging into the fractionating tower is used to maintain a low absolute pressure on the flash tower.

Figure 2 illustrates a diagrammatic view of a modification of our invention in which a thermo-compressor or steam jet pump is used to maintain a low absolute pressure on a flash tower and in which the steam and overhead products from the flash tower are introduced to a fractionating tower at a higher absolute pressure.

Figure 3 illustrates another modification of our invention in which a thermo-compressor or steam jet pump is used to maintain a low absolute pressure on a stripping or flash tower, the exhaust steam and the overhead products from the stripping tower being returned to the fractionating tower.

In general, our invention as disclosed in Figure 1 provides a process by which a reduced crude is heated and flashed to remove the asphalt or flux bottoms. A low absolute pressure is maintained on the flash tower by means of a thermo-compressor which serves to remove as overhead products, the reduced crude vapors and process steam used as a stripping medium. Substantially all the hydrocarbon vapors are condensed out of the steam which is introduced with the jet steam to a fractionating tower to function as a stripping medium. The condensate is reheated progressively by suitable heat exchangers and a tube still before being introduced to the fractionating tower. By condensing the vapors from the flash zone and pumping them as a liquid into the fractionating tower at a higher absolute pressure, the quantity of steam required to transfer vapors and condensate from the flash tower to the frac-

tionating tower is greatly reduced below that required to transfer the whole in the vapor state. The heating of the condensate which is partially due to heat exchange with the vapors from the 5 flash tower raises the temperature of the condensate to a point permitting it to vaporize sufficiently in the fractionating tower to recover the overhead products.

The jet steam from the thermo-compressor and 10 the process steam from the flash tower when introduced to the fractionating tower operating at a higher absolute pressure serve to lower the partial pressure in this tower and effect vaporization at a lower temperature than would be necessary 15 for a single flash system.

The process is also applicable to a system for 20 recovery of heavy cylinder stock from the flux bottoms of reduced crude subjected to fractionation. In this case, as disclosed in Figure 2, 25 the bottoms after heating, if necessary, are flashed, the heavy cylinder stock vapors being taken off overhead. A lower absolute pressure is maintained on the flash tower than on the fractionating tower by a thermo-compressor functioning as before. The condensate in this case may 30 be removed directly as a heavy cylinder stock. However, inasmuch as the quantity of vapors taken off overhead from the flash tower will be much less in this case than in the operation of 35 Figure 1, it may be desirable to introduce these vapors and the jet steam directly into the fractionating tower. The condenser in such case would be bypassed.

The process as applied to Figure 3 is substantially the same as that in Figure 2 save that a side stream stripping tower is substituted for the 40 flash tower. The relatively low quantity of vapors taken overhead may make bypassing of the condenser feasible without greatly increasing the steam consumption of the jet.

Referring now more particularly to Figure 1, an asphaltic reduced crude, for example, is charged through a line 1 to a convection section 2 in a furnace setting 3 where the viscosity is lowered 45 and a preliminary heating takes place. The charge from this section is transferred by means of a line 4 to a radiant heating section 5 of the furnace where the oil is partially vaporized before being introduced through a line 6 to a flash 50 tower 7. Vapors evolved in this tower are taken off overhead through a line 8 which passes through a vapor heat exchanger 9 to a surface condenser 10. Cooling water is fed to this condenser through a line 11 and after circulation is 55 removed through a line 12. A steam jet pump 13 is connected through a line 14 with the receiver of condenser 10 and through line 8 with flash tower 7. Live steam is introduced to the jet pump 13 by means of a line 15. Steam exhausted from the pump 13 is introduced through 60 a line 16 to the bottom of the fractionating tower 17. It is to be understood, however, that line 16 may be connected to the fractionating tower either above or below the flash section or main 65 point of charge entrance to the fractionating tower. The condensate from 10 is pumped from line 18 by pump 19 through heat exchangers 9 and 20 to the convection section 21 of the furnace setting 3. A line 22 connects the convection section 21 with the fractionating tower 17. A line 23 serves as a draw-off line for the bottoms from the tower 7 which pass through the heat exchanger 20 to the cooler 24 and thence to storage. A series of bubble trays 25 are located within the tower 17. A vapor draw-off

line 26 is connected to a condenser 27 which is provided with cooling water through a line 28. A line 30 is provided for the removal of condensate from the receiver 29. A barometric condenser 31 is connected with the receiver 29 5 through a line 32, a vacuum being maintained on the barometric condenser by means of the steam jet air pumps 33 connected therewith through a line 34. A line 35 connects the barometric condenser with the hot well 36. Process 10 steam may be introduced to the flash tower 7 and the fractionating tower 17 by means of lines 37 and 38 respectively.

In operation, oil which may be, for example, reduced asphaltic crude is heated in the convection section 2 and the radiant section 5 of the tube still 3. The heated oil and vapors from the radiant section 5 are introduced into the high vacuum flash tower 7 where, due to the decreased pressure, further vapors are evolved and the 20 asphalt or flux bottoms collected in the bottom of the tower are removed through the line 23 and passed through the cooler 24 before being sent to storage. The steam jet pump 13, by reason of its connection to the flash tower through the 25 lines 14 and 8 serves to maintain this tower under a low absolute pressure of from twenty-five to thirty millimeters of mercury. Process steam introduced into the tower through the line 37 aids in removing the lighter ends from the 30 condensate collected, which light ends pass overhead with the vapors and steam through the line 8 and the vapor heat exchanger 9 to the condenser 10. The oil vapors are condensed 35 therein and the condensate is withdrawn through the line 18 by the pump 19 which delivers the condensate through the vapor heat exchanger 9 and the heat exchanger 20 to the convection section 21 of the tube still 3. This condensate is heated in this convection section before being 40 introduced to the fractionating tower 17 through line 22. The steam and uncondensed overhead products of flash tower 7 which remain uncondensed in the condenser 10 are withdrawn from the receiver by the steam jet pump 13 by entrainment with the live steam introduced through the line 15. The steam exhausted from this pump is delivered directly to a selected point of the fractionating tower by the line 16. A subatmospheric pressure higher than that which exists in the flash tower is maintained in the fractionating tower 17 by means of the barometric condenser 31 and vapor condenser 27 pulling through the line 26 to the top of the fractionating 45 tower. For example, the fractionating tower 50 may be maintained at an absolute pressure of about seventy-five millimeters of mercury. Process steam introduced through the line 38 at the bottom of the tower aids in stripping the light ends from the tower bottoms. The steam introduced into the tower from the steam jet pump through line 16 also acts as a stripping medium. The bottoms product in the tower, for example, a cylinder stock, is removed through the line 39 55 and delivered to storage. The oil vapors and steam taken off overhead through the line 26 are condensed in condenser 27 and separated in receiver 29, gas oil being delivered as condensate through the line 30 to storage while the steam is withdrawn and condensed by the barometric condenser 31. It will be observed that we are enabled to produce an asphalt of low penetration from the flash tower with an increased yield of cylinder stock from the main tower by discharging the exhaust of the steam jet pump and the 60 65 70 75

steam from the flash tower into the bottom of the fractionating tower. By our process the temperature necessary to produce vaporization is lower than would usually be required, due to the 5 partial pressure effect of the steam and light ends.

Referring now to Figure 2, fractionating tower 17 is connected to a flash tower 7 by means of the line 39 having a pump 40. A vapor outlet line 8 connects the vapor condenser 10 and the top of the flash tower 7. A bypass line 8a connects the vapor line 8 with a steam jet pump 13 while the line 14 having a shut-off valve 14a connects the steam jet pump to the vapor condenser 10. A 10 shut-off valve 10a placed in the line 8 serves to cut the vapor condenser from the line 8 in the event that the steam jet pump 13 is desired to be directly connected to the flash tower 7. A valve 8b is placed in line 8a for a purpose which 15 will be more fully described hereinafter. The outlet from the steam jet pump is connected to discharge into the bottom of the fractionating tower 17 by means of a line 16. It is to be understood, however, that this is by way of example 20 only and that this line 16 may be connected to the fractionating tower either above or below the flash point in the fractionating tower. A condensate draw-off line 18 having a pump 19 is connected to the bottom of the receiver 10b and 25 serves to deliver the liquid hydrocarbons to storage. Process steam may be introduced, if desired, to the fractionating tower and flash tower by means of the lines 38 and 37 respectively. It 30 is to be understood, however, that we contemplate operating the flash tower either under a wet or dry vacuum. A vapor draw-off line 26 is connected to the usual steam jet and barometric condenser as in Figure 1. If it is desired, a convection tube bank 41 in tube still 3 may be connected to the line 39 and so arranged that, by manipulation of the valves 42 and 43, bottoms withdrawn from the fractionating tower may be delivered to the flash tower with or without pre-heating as may be desired.

45 In operation, the flux bottoms of the fractionating tower 17 are pumped by the pump 40 through the line 39 or 39a to the flash tower 7 where the oil is vaporized either with or without process steam and the vapors and steam taken off overhead through the line 8. A high vacuum of from ten to twenty-five millimeters of mercury is maintained in the flash tower as a result of the 50 operation of the steam jet pump 13 and the vapor condenser 10. The overhead products from the flash tower comprising, for example, oil vapors and steam, may be delivered to the vapor condenser 10 wherein oil vapors are condensed, the condensate being withdrawn through line 18 by means of pump 19 and sent to storage. The uncondensed products are entrained by the high 55 velocity jet 15 of the steam jet pump 13. In this event, uncondensed products from the flash tower and the jet steam are delivered together through the line 16 to a selected point above or below the flash point in the fractionating tower 17. In the 60 case of asphalt bottoms being flashed in the tower 7, any material taken overhead would probably be cooled sufficiently by the steam jet pump so that it would be returned to the fractionating tower partly as a liquid. In order to prevent contamination of the bottoms in the fractionating tower, a return of the flash tower overhead condensate to a point above the point of cylinder stock draw-off would be advisable, 65 instead of returning this condensate to the base 70

of the fractionating tower. It may be desired to deliver the overhead products from the flash tower directly to the steam jet pump 13. In such case the valves 10a and 14a would be closed and the valve 8b opened. Steam and oil vapors from the flash tower delivered to the steam jet pump 13 would be directly compressed and delivered together to the fractionating tower 17.

Referring now to Figure 3, the fractionating tower 17 is connected by means of a sidestream withdrawal line 39 to the stripping tower 7, from which a condensate withdrawal line 23 leads to storage. Stripping steam may be introduced into the stripping tower 7 by means of the line 37. The light ends and stripping steam from this 10 stripping tower 7 are taken off overhead through the line 8. A condenser 10 is connected to the line 8 and to a steam jet pump 13 by a line 14 having a valve 14a. An auxiliary line 8a having a valve 8b connects the vapor draw-off line 8 with the steam jet pump 13. The valve 10b is provided in the connection between the condenser 10 and the line 8. A condensate withdrawal line 18 connects the condenser 10 with a selected point 15 on the fractionating tower 17. The products exhausted from the steam jet pump 13 may be returned to the fractionating tower through the line 19 having a valve 19a. It is to be understood however, that the location of these return lines with respect to the flash point 22 of the fractionating tower is by way of example only, it being within the contemplation of our invention to return the exhausted products to any selected 20 point up and down the tower.

In operation, oil is heated and introduced into 25 the fractionating tower 17 at the point of flash 22. The vapors evolved rise upward through the tower forming pools of condensate on the various fractionating plates. A selected fraction is withdrawn as a side stream through the line 39 30 and introduced to the top of the stripping tower 7 wherein the light ends are stripped by steam entering through the line 37. The stripped oil is delivered to storage through the line 23. The vaporized light ends and stripping steam are 35 taken off overhead through the line 8. If separation of the oil vapors and steam is desired, the valves 10a and 14a are opened and the valve 8b is closed. Oil vapors will then be condensed in the condenser 10 and delivered as a condensate 40 through the line 18 to the fractionating tower 17 while the uncondensed products are entrained by the steam jet 15 of the pump 13 and delivered with the exhaust steam through either the line 16 45 or 19 to the fractionating tower 17. The point 50 of return, of course, will depend upon the character of the side stream being stripped. It may be desirable, when the amount of overhead vapors is small, to compress the stripping steam and vapors together by means of the steam jet pump 60 and deliver the products exhausted from this pump directly to the fractionating tower 17. In such a case the valves 10a and 14a will be closed and the valve 8b opened so that the overhead products will be delivered directly to the steam jet 65 pump without passage to the condenser. A vacuum is pulled on the main fractionating tower by means of a steam jet and barometric condenser connected to the line 26 as in Figure 1. This vacuum is less than that existing in the 70 stripping section.

It will be observed that we have accomplished the objects of our invention. We have provided a high vacuum system of double flash distillation in which a thermo compressor or steam jet pump 75

is used to create a high vacuum in a stripping section or flash tower. At the same time this serves to return the stripping steam and exhaust steam jet to a fractionating tower at a less vacuum in order that the partial pressure effect of the steam may be utilized to cause vaporization in the fractionating tower at a lower temperature than is possible with a single flash system of distillation.

It will be understood that certain features and sub-combinations are of utility and may be employed without reference to other features and sub-combinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Having thus described our invention, what we claim is:

1. A process for distilling hydrocarbon oils including the steps of heating a hydrocarbon oil, vaporizing lighter hydrocarbons of the heated oil in a flash zone in the presence of steam, removing hydrocarbon vapors and steam from the flash zone and condensing the vapors from the steam and vapors in a condensing zone, removing uncondensed vapors and steam from the condensate formed in the condensing zone by entraining the vapors and steam with a high velocity steam jet in an entrainment zone whereby the condensing zone and the flash zone are subjected to a low absolute pressure, removing the condensate from the condensing zone, heating the condensate and introducing it into a fractionating zone having a higher absolute pressure at the point of flash than that in the flash zone and discharging the jet steam and entrained products from the entrainment zone into the fractionating zone.

2. The process of claim 1 in which the absolute pressure in the flash zone is between twenty-five and thirty millimeters of mercury, and the absolute pressure in the fractionating zone at the point of flash is about seventy-five millimeters of mercury.

3. A distillation process comprising the steps of introducing into a stripping zone a stream of heated oil, subjecting the heated oil therein to a sub-atmospheric pressure whereby relatively light hydrocarbons of the oil are vaporized, continuously removing a stream of vapor from said stripping zone and passing the vapor stream through a condensing zone, subjecting the vapor stream during its passage through said condensing zone to a sub-atmospheric pressure and cooling the vapor whereby a vapor condensate is formed, entraining vapor uncondensed in said condensing zone with a high velocity steam jet to increase the pressure on said uncondensed vapor and to maintain a sub-atmospheric pressure in said condensing zone and in said stripping zone, separately heating a stream of the vapor condensate, introducing the stream of heated

condensate into a fractionating zone and subjecting said condensate therein to a sub-atmospheric pressure higher than that in said stripping zone, and effecting a separation of said condensate in said fractionating zone into a plurality of fractions of successively higher boiling points, and discharging said jet steam and entrained vapor into said fractionating zone.

4. A process for separating cylinder stock and a low penetration asphalt from asphalt containing reduced crude petroleum oil comprising the steps of flowing the oil through a heating zone wherein the oil is heated and into an enlarged flash zone wherein the heated oil is subjected to a sub-atmospheric pressure sufficiently low to vaporize a majority of hydrocarbons lower boiling than the desired asphalt product, stripping the unvaporized oil in the flash zone with steam to vaporize substantially the remainder of hydrocarbons lower boiling than the desired asphalt product, removing the stripped oil from the flash zone and from the process as the desired low penetration asphalt product, separately removing a mixture of the oil vapors and the stripping steam from the flash zone and passing the mixture without substantial change in pressure through a cooling and condensing zone wherein oil vapors are condensed out of the mixture, pumping the oil condensate through a heating zone wherein it is heated and into a fractionating zone wherein the heated oil condensate is subjected to a sub-atmospheric pressure which in the region where the heated oil condensate enters is higher than the pressure in said flash zone yet sufficiently low as to vaporize the majority of hydrocarbons lower boiling than the desired cylinder stock product, stripping the unvaporized oil condensate in said fractionating zone with steam to vaporize substantially all remaining hydrocarbons lower boiling than the desired cylinder stock product and removing the stripped oil condensate from the fractionating zone and the process as the desired cylinder stock product.

5. A process for distilling hydrocarbon oils which comprises, heating a hydrocarbon oil, vaporizing relatively low boiling hydrocarbons of the heated oil in a flash zone, separately removing unvaporized oil and oil vapors from the flash zone and diverting the unvaporized oil from the process, cooling the removed vapors in a condensing zone to form a vapor condensate, maintaining a sub-atmospheric pressure in the flash and condensing zones by entraining vapors uncondensed in said condensing zone with a steam jet, discharging the jet steam and entrained vapors into a fractionating zone, heating the vapor condensate, introducing the heated condensate into said fractionating zone wherein the absolute pressure in the region of introduction of the heated condensate to said zone is higher than that in said flash zone and fractionating the condensate in said fractionating zone.
